UNITED STATES PATENT OFFICE

ROBERT J. PARDEE, OF CLEVELAND HEIGHTS, OHIO, ASSIGNOR TO THE CLEVELAND PUNCH & SHEAR WORKS COMPANY, OF CLEVELAND, OHIO, A CORPORATION OF OHIO

DRAWING PRESS

Application filed June 8, 1928. Serial No. 283,920.

This invention relates generally to drawing presses and more particularly to one in which the blank holder and drawing die are operated from one and the same crank shaft 5 and in which a series of links and levers are employed to cause the blank holder to dwell for a definite period in holding contact with the work blank during the shaping or punching movement of the drawing die connected 10 to the plunger.

An object of the invention is to provide a novel arrangement of the improved means employed for communicating the requisite movements and dwells to the blank holder 15 from the crank shaft and whereby the blank holder is given a more perfect dwell in work-holding position, thus insuring perfect work without the use of cushioning means.

Another object is to provide a press of this 20 character in which the main crank shaft or shafts and other blank holder operating parts are all carried by the crown of the press and whereby a simpler and more economical construction can be had and the operation of the 25 machine as a whole made easy.

With these various objects in view the invention consists in the novel features of construction and in the manner of combining or arranging the same all of which will be fully 30 described hereinafter and set forth in the appended claims.

In the drawings forming a part of this specification, I have illustrated one embodiment of my invention and in which Fig. 1 is 35 a face view of the press; Fig. 2 is an end view of the same with the various parts in their raised positions; Fig. 3 is a similar view showing the parts in their lowered positions; Fig. 4 is a face view of the crown of the frame and also the side pieces thereof; and Fig. 5 is an 40 end view of said parts in detail.

In constructing the press in accordance 45 with my invention I employ a base 10 constituting the bed of the press and adapted to support a die (not shown) complementary to the drawing die connected to the plunger herein-after referred to. At each end of the base or 50 bed piece 10 are arranged the uprights 11 extending upwardly a considerable distance and upon the upper ends of these uprights 11 are

arranged the end pieces 12 of the crown of the machine, said end pieces being united by the top central yoke 13, as most clearly shown in Figs. 4 and 5. Tension rods 14 pass through the side pieces of the crown and likewise the 55 standards or side pieces 11 into the base 10 thereby securely uniting these various parts, constituting what may be termed the frame of the press. The crown, in addition to the end pieces 12 and central yoke 13, is also provided with downwardly extending legs 15 and horizontal braces 16 connect these depending legs and the end pieces 12 of the crown.

The end pieces 12 are each formed with 60 openings 17 which are arranged in horizontal alignment with each other and through which the crank shaft 18 is inserted, this crank shaft being connected to the crown by means of caps 19 next to the side pieces 12 in the opening 17 and by caps 20 which are connected to the ends of the legs 15, it being understood that the top sides of the openings 17 and the ends of the legs 15 are curved out to provide one-half of the bearing while the caps 19 and 20 provide the remainder of the bearing for 65 the said crank shaft.

Connecting rods 21 are connected to the drawing die or punch 22 at their lower ends and to the crank portions 18^a of the crank 70 shaft so that as the crank shaft is rotated the drawing die or punch will be reciprocated vertically for the purpose of effecting the drawing or punching operation. The opposite ends of the crank shaft 18 project beyond the end pieces of the crown a short distance and mounted upon each projecting end of the crank shaft is a large gear 23, said gears 23 meshing with and being driven by 75 gears 24 on a shaft 25 which in turn carries gears 26 meshing with gears 27 arranged upon the shaft 28 to which power is applied through a pulley 29 receiving its power from any suitable source. The shafts 25 and 28 are arranged at what may be termed the rear side 80 of the machine as will be apparent from Figs. 1, 2 and 3.

The mechanism thus far described is for 85 the reciprocation of the drawing die or punch at the proper rate of speed and with the re- 90

quisite power for accomplishing its operations. I also propose to utilize this same general power for the reciprocation of the blank holder and it will of course be understood that for the proper function of the blank holder it is necessary that it operate in unison to a certain extent with the drawing die or punch but that the same should have a considerable dwell or rest for the purpose of holding the blank or material during the drawing or punching operation, and with the object of producing this reciprocation of the blank holder with this predetermined period of rest or dwell I provide a novel arrangement of links and levers which I shall now describe.

Each gear 23 carries a crank pin 23^a and to which is connected the upper end of a connecting rod 30, the lower end of each connecting ring being connected to a slide 31 traveling vertically in the gibs or guides 32 arranged upon the exterior of the uprights 11. On the exterior of each end piece 12 of the crown of the frame there are mounted levers or rocker arms 33 and also connected to the exterior of each end piece 12 of the crown and above the levers or rocker arms 33 are mounted a second set of levers or rocker arms 34 and links 35 are employed to connect the upper ends of the rocker arms 33 with the lower ends of the rocker arms 34. Connecting rods 36 connect the lower ends of the rocker arms 33 with the slide 31 and the reciprocation of the slide through these connecting rods 36 actuates the rocker arms 33. The upper ends of the rocker arms 34 have links 37 connected thereto which links in turn are pivotally connected to the arms 38 carried at the ends of the rock shafts 39 attached to the front and rear faces of the crown by bearing caps 40. Each rock shaft 39 carries intermediate its ends, and adjacent the end pieces 12 of the crown, the parallel arms 41 to which are connected connecting rods 42 which, at their lower ends, are pivotally connected to the cross head 43 to which in turn is adjustably connected the blank holder 44 and it will be understood that the drawing die or punch 22 works through or within the blank holder 22 in the completion of its punching or drawing functions.

It will thus be seen that power is applied to the crank shaft and this same power is employed to reciprocate the slides 31 at opposite ends of the frame and from these slides motion is communicated to the rocker arms 33 and from these rocker arms 33 to the rocker arms 34 through the medium of the links 35 and from the rocker arms 34 to the rock shafts 39 through the medium of the links 37 and arms 38. A rocking motion of the shafts 39 at the front and rear of the machine is communicated to the blank holder through the medium of the arms 41 extending from the rock shafts and the connecting rods 42 which

in turn connect the arms 41 to the cross heads 43 to which the blank holder is adjustably united. The rocker arms or levers 33 and 34 are angular in shape as shown, the angularity of the arms 33 being somewhat more acute than that of the arms or levers 34.

By means of the levers, links and connecting rods constructed and arranged as herein shown and described I am able to obtain a perfect dwell of the blank holder at the lower limit of its stroke at approximately 120° rotation of the crank shaft from the point X to the point Y as indicated in Figs. 2 and 3. This is due to the fact that a slight up and down movement given the slides by the crank pins passing from the point X to the point Y is completely absorbed in the toggle action between the various rocker arms, links, rock shafts, arms and connecting rods.

It will be readily seen by reference to Figs. 2 and 3 that there are three distinct toggle actions and these in combination with the movement of the crank pin passing over the top center are for points of dissipation of movement and thereby permitting the desired dwell of the blank holder at the proper time with reference to the drawing or punching movement of the drawing die or punch.

It will thus be seen that I provide a strong and durable press embodying a comparatively few operative parts so constructed and arranged as to provide both ease and accuracy of operation and it will also be noted that all of the operative parts with the exception of the slides are carried by the crown portion of the main frame. The crank shaft in my improved construction is carried entirely within the crown portion in contrast with being interposed between the crown and main portion of the frame as commonly arranged. By the arrangement of the crank shaft entirely within the crown portions, as herein shown and described, in combination with the rocker arms, links and rock shafts, as herein arranged, I am enabled to improve the ease and steadiness of the operation of the press under the high pressures required in the proper performance of the work required of presses of this nature.

Having thus described my invention, what I claim is:—

1. In a press of the kind described, the combination with a frame, a blank holder and a punch, of a crank shaft carried by said frame, and to which said punch is operatively connected, a slide reciprocally mounted on an end of the frame and operatively connected with the crank shaft, a pair of rock shafts mounted on said frame adjacent the upper end thereof, one of said rock shafts being mounted adjacent the front of the press and the other adjacent the rear thereof, an arm fixedly carried by each of said rock shafts intermediate its ends, another arm carried by each of said rock shafts at an end

thereof and extending at an angle to said first mentioned arms, links connecting said first mentioned arms directly to said blank holder, and means connecting said second mentioned arms with said slide, said means including a pair of angled levers on an end of the press adjacent the front thereof mounted one above the other below said rock shafts and above said slide, a second pair of levers similarly mounted adjacent the rear of said press, a pair of connecting rods, one end of each being connected to said slide, the opposite end of one connecting rod being connected to one end of the lowermost lever of the first mentioned pair of angled levers, and the other end of the other connecting rod being connected to one end of the lowermost lever of the second mentioned pair of angled levers, a pair of links, one of said links having one end connected to the other end of the lowermost angled lever of the first mentioned pair and the other end connected to the adjacent end of the upper lever of the first mentioned pair, the other link similarly connecting the levers of the second mentioned pair, a second pair of links, one of said links having one end connected to the other arm of the upper lever of the first mentioned pair and the other end connected to the arm on the end of the adjacent rock shaft and the second link similarly connecting a second pair of angled levers to the other rock shaft.

2. In a press of the kind described, the combination with a frame, blank holder and punch, of a crank shaft to which said punch is operatively connected, a slide reciprocating on an end of the frame and operatively connected with the crank shaft, rock shafts arranged upon the frame at the upper portion thereof, each of said rock shafts carrying arms connected by links with the blank holder, and other arms extending at an angle to said first arms, and means for operatively connecting the slide with the rock shafts, said means including connecting rods, a pair of angled levers mounted on one end of said frame, one at each side thereof, one end of each of said connecting rods being connected to said slide, the other ends being connected, one to one arm of each of said angled levers, a second pair of angled levers mounted on one end of said frame above said first angled levers and below said rock shafts, one at each side thereof, links, one connecting the other arm of each of said first pair of angled levers with one arm of one of said last angled levers, and links, each having one end connected to the other arm of one of said last angled levers and the other end connected to one of said other arms of said rock shafts, the angle of the first mentioned pair of angled levers being more acute than the angle of the second mentioned pair.

connected with the crank shaft, rock shafts arranged upon the frame at the upper portion thereof, each of said rock shafts carrying arms connected by links with the blank holder, and other arms extending at an angle to said first arms, and means for operatively connecting the slide with the rock shafts, said means including connecting rods, a pair of angled levers mounted on one end of said frame, one at each side thereof, one end of each of said connecting rods being connected to said slide, the other ends being connected, one to one arm of each of said angled levers, a second pair of angled levers mounted on one end of said frame above said first angled levers and below said rock shafts, one at each side thereof, links, one connecting the other arm of each of said first pair of angled levers with one arm of one of said last angled levers, and links, each having one end connected to the other arm of one of said last angled levers and the other end connected to one of said other arms of said rock shafts, the angle of the first mentioned pair of angled levers being more acute than the angle of the second mentioned pair.

In testimony whereof, I hereunto affix my signature.

ROBERT J. PARDEE.
